UNITED STATES PATENT OFFICE.

FRANK M. PRIEST, OF RUSK, TEXAS.

BOOKSTAND.

Application filed October 21, 1921. Serial No. 509,372.

To all whom it may concern:

Be it known that I, FRANK M. PRIEST, a citizen of the United States, and a resident of Rusk, in the county of Cherokee and State of Texas, have invented a new and Improved Bookstand, of which the following is a full, clear, and exact description.

This invention relates to improvements in book stands, an object of the invention being to provide a device of this character which will be particularly useful in county clerk's offices and other places where it is necessary to copy from or make entries in large heavy books or large manuscripts.

An object of the invention is to provide a stand of this character, in which the book supporting member is adjustable both vertically and angularly, and a stand which will be strong, durable and efficient in use, simple and practical in construction, neat and attractive in appearance, and comparatively inexpensive to manufacture.

With these and other objects in view, the invention consists in certain novel features of construction and combinations and arrangements of parts as will be more fully hereinafter described and pointed out in the claim.

In the accompanying drawings:

Figure 1 is a view in side elevation of the stand;

Figure 2 is a view in rear elevation of the book supporting platform showing its manner of connection to the standard; and

Figure 3 is an enlarged fragmentary detail view on the section line 3—3 of Figure 1.

Referring in detail to the drawings, my improved stand, which is preferably formed entirely of metal, comprises a base 1. This base includes a plurality of laterally extending legs 2 supported upon casters 3. The reference numeral 4 designates a hollow standard rising from and preferably screwed into the base. A rod 5 telescopes in the standard and is provided throughout its length with a series of openings 6, in any one of which, a pin 7 mounted in the standard is engageable.

8 represents a book supporting platform or table. A pair of angular plates 9 are secured to the under face of the intermediate portion of the table and are pivoted in the

bifurcated upper end of the rod 5 upon a screw 10. A clamping nut 11 associated with the screw permits the table or platform to be locked at any desired angle relative to the standard.

It will be noted that the table is formed from a single sheet of metal bent to provide a relatively deep recess 12 at its intermediate portion, which receives the back of a book and a pair of offset wing portions 13, receiving the covers of the book.

It will thus be seen that I provide a book stand which is adjustable vertically and a platform which is angularly adjustable relative to the vertical plane of the standard.

Although I have illustrated one of the preferred embodiments of my invention, it will be evident that various slight changes and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended claim.

I claim:

A book stand, consisting of a base mounted on casters, a hollow standard detachably secured to the base and provided adjacent its upper end with a transverse opening, a rod having a bifurcated and apertured upper end and provided with a plurality of openings, said rod telescoping in the standard, a pin passing through the opening of the standard and adapted to engage any of the openings of the rod to permit of vertically adjusting said rod, a comparatively large platform having a longitudinal depression and provided on the rear face of its depression with a curved and apertured member projecting therefrom, said member extending between the members of the bifurcations of the rod, and a bolt passing through the members of the bifurcations and the curved member of the platform and provided with a nut whereby the platform can be adjusted at different angles and locked in the position to which it has been adjusted.

FRANK M. PRIEST.
